UNITED STATES PATENT OFFICE.

JOHN P. SCHAN, OF BROOKLYN, NEW YORK.

DESIGN FOR A BATHING-CAP.

45,917.

Specification for Design.

Patented June 9, 1914.

Application filed January 26, 1914. Serial No. 814,598. Term of patent 7 years.

To all whom it may concern:

Be it known that I, JOHN P. SCHAN, citizen of the United States, residing at 1098 Halsey street, in the city of Brooklyn, county of Kings, State of New York, have invented a new, original, and ornamental Design for a Bathing-Cap, of which the following is a specification, reference being had to the accompanying drawing, forming a part thereof.

I claim:

The ornamental design for a bathing cap as shown.

JOHN P. SCHAN.
